UNITED STATES PATENT OFFICE

2,191,130

LOADING DEVICE

William Ludwig, Bruno, Saskatchewan,
Canada

Application May 3, 1937, Serial No. 140,547

1 Claim. (Cl. 42—87)

This invention relates to improvements in loading devices and has particular reference to a device for loading rifles, repeating guns, and the like.

5 The principal object of this invention is to provide a magazine wherein a plurality of cartridges may be stored and then dispensed into the gun or rifle quickly and of a predetermined number.

10 A further object is to produce a device of this character which is compact, readily transportable, and a container which is a safety factor in transporting such explosive ammunition.

15 A further object is to produce a device which is economical to manufacture.

Other objects and advantages will be apparent during the course of the following description.

In the accompanying drawing forming a part 20 of this specification and in which like numerals are employed to designate like parts throughout the same,

Fig. 1 is a side elevation of my device;

Fig. 2 is a side elevation showing the device inverted from that of Fig. 1;

Fig. 3 is a cross sectional view taken on the 25 line 3—3 of Fig. 1 and on an enlarged scale;

Fig. 4 is a fragmentary detailed cross sectional view taken on the line 4—4 of Fig. 1; and

Fig. 5 is an enlarged fragmentary detailed view 30 of the pawl actuating plunger rod and spring therefor.

Many rifles include a magazine in which a number of cartridges are stored. This type of rifle is commonly termed a "repeating gun", in that several shots may be made before it is necessary to recharge with fresh ammunition. In shooting galleries, it is particularly advantageous to have some means for quickly recharging these rifles and with a predetermined number of cartridges.

40 I have, therefore, devised a holder wherein a plurality of stacked cartridges are so positioned that a single stack may be quickly released into the magazine of the rifle.

In the accompanying drawing wherein for 45 the purpose of illustration is shown a preferred embodiment of my invention, the numeral 5 designates a receptacle having a window 6, and within this receptacle are parallel cartridge holders 7. These cartridge holders may be of any desired number and extend from the top to the bottom of the receptacle. A sliding bottom is shown at 8 and a sliding top at 9. The top has a tubular extension 11 which communicates with the interior of the receptacle. A sliding gate 12 is controlled by a thumb piece 13 so

that the opening through the tubular member 11 may be obstructed when desired. Secured to the underside of the top 9 is a ratchet 14, which is adapted to be engaged by a gravity actuated pawl 16 pivotally mounted to one end of the rod 17, which passes through a spring chamber 18 and terminates in a thumb piece 19. A spring 21 surrounds the rod 17 and abuts a slider 22, secured to the rod 17, and has its opposite end engaging the bottom of the spring chamber 18. 10 A guide rod 23 is also connected to the thumb piece 19 and passes through a guide 24, fastened to the opposite side of the receptacle from the spring chamber 18. A spring 26 engages the underside of the sliding top 9 and holds the 15 same in adjusted position.

The operation of my device is as follows:

Assuming the same has been loaded with cartridges, as indicated in Fig. 1, where two of the cartridge holders have been filled, and that the 20 device is inverted over the magazine of a rifle, then by moving the thumb piece 19, the top 9 will be moved into alignment with one of the cartridge holders 7; and by opening the sliding gate 13, any cartridges which are in the cartridge holder in alignment with the tube 11 will slide therefrom through the tube and into the magazine of the rifle. By again actuating the thumb piece, the top will be slid into alignment with the next cartridge holder, and the next 25 group will likewise be discharged.

It will thus be seen that with my device a rifle may be quickly loaded with any desired number of cartridges.

It is to be understood that the form of my 35 invention herewith shown and described is to be taken as a preferred example of the same and that various changes relative to the material, size, shape and arrangement of parts may be resorted to without departing from the spirit 40 of the invention or the scope of the subjoined claim.

Having thus described my invention, I claim:

A loading device for cartridges including a 45 receptacle, a plurality of parallel tubular holders mounted in said receptacle, a horizontal sliding top secured to said receptacle and having a tube forming an opening therethrough, a sliding gate extending through said tube, a ratchet positioned on said top and engaging a pivoted gravity dog associated therewith which when reciprocated will move said tube progressively 50 into alignment with said parallel holders, and a sliding bottom for said receptacle, whereby access to both ends of said holder may be had. 55

WILLIAM LUDWIG.
